(57) **CLAIM**

The ornamental design for a shotgun case, as shown and described.

DESCRIPTION

FIG. 1 is a top, front and left side perspective view of a shotgun case showing my new design;

FIG. 2 is a top, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled "9" in FIG. 1; and,

FIG. 10 is an enlarged view of the portion labeled "10" in FIG. 2.

The dotted lines shown on the shotgun case depict stitching that form no part of the claimed design. The dot-dash broken line rectangle frames define the boundary of an enlarged view and form no part of the claimed design.
